ATTORNEYS.

UNITED STATES PATENT OFFICE.

FRANK H. NEFF, OF SOUTH EUCLID, OHIO, ASSIGNOR TO THE ELECTRIC RAILWAY IMPROVEMENT COMPANY, OF CLEVELAND, OHIO, A CORPORATION OF OHIO.

RAIL BOND.

Application filed April 12, 1928. Serial No. 269,500.

The present improvements, relating, as indicated, to rail bonds, have more particular regard to bonds which have bodies composed of laminations or strands and which are designed to have their terminals attached to the rail either by an arc or gas flame. This method of attaching bonds of the type in question obviously presents a number of difficulties if the ends of such a laminated or stranded conductor body are to be all homogeneously united with the adjacent rail face. As is well understood, the bond body is usually composed of copper or equivalent metal of relatively lower melting point than the steel of the rail, and due to the fact that the metal, copper, has no plastic or pasty condition as it approaches the melting temperature, but disintegrates from the solid state to beads of melted copper which exude from the solid, leaving a porous brittle structure commonly called burnt copper and generally known to be very weak mechanically, special provision requires to be made in the design and assembly of elements that enter into the bond terminal so that the ends of the component strands will not be burnt off but united by a solid mass of metal with the rail face.

One object of the present invention is to provide a bond of the type in question with a terminal that includes a sleeve of special design and construction, whereby the strands that enter into the terminal are properly presented and held in place for union with the rail in the manner described, i. e., by solid mass of built up metal formed through the agency of an electric arc or gas flame of corresponding high temperature. At the same time such terminal sleeve is constructed so as to somewhat more flexibly confine the strands where they enter the terminal and thus avoid the danger of such strands becoming broken due to vibration as is apt to be the case if they directly enter the solid portion of the finished terminal or are too rigidly confined by such sleeve.

To the accomplishment of the foregoing and related ends, the invention, then, consists of the means hereinafter fully described and particularly pointed out in the claims, the annexed drawing and the following description setting forth in detail certain mechanism embodying the invention, such

disclosed means constituting, however, but one of various mechanical forms in which the principle of the invention may be used.

In said annexed drawing:

Fig. 1 is a plan view of a bond embodying my present improvements; Fig. 2 is a side elevation of the same, one end being shown in longitudinal section, as indicated by the line 2—2, Fig. 1; Fig. 3 is a plan view of a shaped, stamped or equivalent piece of metal from which the sleeve that forms a feature of the terminal is formed, as such piece appears previously to being applied to the bond body; Fig. 4 is a transverse section through such piece, as indicated by the line 4—4, Fig. 3; Fig. 5 is a plan view of one terminal of a bond similar to the one shown in Fig. 1, but illustrating a modification in the construction of the sleeve; Fig. 6 is a transverse section of such terminal, the plane of such section being indicated by the line 6—6, Fig. 5; Fig. 7 is a plan view of such modified sleeve in initial or developed form; and Figs. 8 and 9 show elevations of two other modified forms of bond terminal embodying the present improvement.

In the several bonds thus illustrated, as generally in bonds of the type hereinbefore referred to, the body 1 is of flexible stranded construction, e. g., twisted copper cable, and the ends of such cable are respectively enclosed in sleeves that constitute thereof the terminals whereby the bond is attached to the rail. These sleeves will preferably be likewise made of copper, although they may be made of ferrous metal, if desired.

In certain general respects the two forms of such terminal sleeve, respectively illustrated in Figs. 1 to 4, inclusive, and 5 to 7, inclusive, are similar to that described and claimed in my pending application filed October 24, 1927, Serial No. 228,217. In other words, such sleeve in each case will be of relatively heavy cross-section and is most conveniently fashioned by being cut or stamped from sheet metal and rolled into tubular form. Thus the sleeve illustrated in the first series of figures will be made from a stamping 2^a having the shape illustrated in Fig. 3, the stamping being adapted to be cut as successive pieces from a straight strip of metal having the cross-section shown in

Fig. 4. Whether fashioned in this way or otherwise the stamping, it will be noted, has its longer edge formed with a projecting lip or flange 2^b of reduced thickness, and when 5 the piece of metal is thereupon rolled to form the sleeve, such flange is placed on the inside, i. e., so as to contact with the stranded material of the bond body 1. It will be understood that the sleeve may be 10 thus rolled or formed incidentally to the application thereof to the end of the bond body, or it may be applied as a sleeve to the latter and subsequently compressed tightly on such end. In either case the parallel or meeting edges will desirably be 15 brought into closely contacting relation so as to form in effect a seam 3.

As a result of the shape of the piece or stamping 2^a, after the terminal sleeve 2 formed therefrom has been applied to the end of the bond, the outer end of the sleeve presents the sloping or beveled appearance best shown in Fig. 2, although, if desired, the same effect may be obtained by cutting 25 away the end of the cylindrical sleeve, the objective being that such end in the finished article should lie in a plane inclined to the axis of the finished sleeve. The end of the bond body is likewise cut away on a plane 30 inclined to its axis (which of course coincides with the axis of the sleeve) but at an angle somewhat more acute to the vertical. As a result, the lower strands, i. e. those adjacent the longer side of the sleeve, will 35 lie approximately flush with such sleeve, but the remaining strands will project more and more therebeyond.

Referring to the opposite or inner end of the sleeve, it will be noted that the strands 40 are here enclosed by the projecting flange like portion 2^b that forms an extension of the sleeve proper and is of thin enough gauge to permit the strands to flex somewhat since they are not so tightly gripped 45 as by the heavier sleeve itself. Furthermore, such flange extension will be well without the zone of solidified metal that results from the arc welding or gas welding of the terminal to the rail.

50 In the modified construction illustrated in Figs. 5, 6 and 7, the sleeve 4 is in all respects like sleeve 2 just described, being preferably made from a flat piece or stamping 4^a similar to piece 2^a, except that the flange extension 4^b is at least in part of greater length than the edge from which it projects. As a result, when the piece is rolled up to form the sleeve, the projecting corners 4^c of the flange will overlap, as clearly shown in Figs. 55 5 and 6. The flange extension 4^b of the sleeve when applied to the terminal will accordingly remain at all times closed even though the strands due to flexure should tend to spread said flange somewhat.

60 65 The bond terminal illustrated in Fig. 8 is

designed to be applied to the rail in vertical position rather than in the horizontal position for which the previously described terminals are adapted. The sleeve 5 here employed does not require to have its outer 70 face beveled off but will present a ledge on which the molten metal formed during the operation of attaching the bond may accumulate. The other end of the sleeve, however, is formed with a flange extension similar 75 to those which feature the sleeves 2 and 4 and such extension subserves the same function 80 here as before.

Another type of bond designed for horizontal attachment is illustrated in Fig. 9, 80 but the sleeve 6 here employed is a solid sleeve and of somewhat different form from the sleeves 2 and 4. However, it is here again desirable to utilize the feature of an integral flange extension 6^a at the inner 85 edge of the sleeve, such flange surrounding the stranded conductor body where it enters the terminal and assisting to preserve the latter just the same as in the previously 90 described constructions of bond.

95 Other modes of applying the principle of my invention may be employed instead of the one explained, change being made as regards the mechanism herein disclosed, provided the means stated by any of the following claims or the equivalent of such 95 stated means be employed.

I therefore particularly point out and distinctly claim as my invention:—

1. As an article of manufacture, a rail 100 bond having a stranded conductor body, a terminal formed of the end of said body, and a metal sleeve surrounding said terminal, said sleeve being formed at its inner end with an integral extension of reduced 105 thickness flexibly encasing the corresponding portion of said body.

2. As an article of manufacture, a rail bond having a stranded conductor body, a terminal formed of the end of said body, 110 and a metal sleeve surrounding said terminal, said sleeve being formed at its inner end with relatively thin, integral, flange-like extension flexibly encasing the corresponding portion of said body.

115 3. As an article of manufacture, a rail bond having a stranded conductor body, a terminal formed of the end of said body, and a metal sleeve surrounding said terminal, said sleeve being longitudinally split 120 and formed at its inner end with an integral extension of reduced thickness flexibly encasing the corresponding portion of said body.

125 4. As an article of manufacture, a rail bond having a stranded conductor body, a terminal formed of the end of said body, and a metal sleeve surrounding said terminal, said sleeve being longitudinally split 130 and formed at its inner end with a relatively

thin, integral, flange-like extension flexibly encasing the corresponding portion of said body.

5. As an article of manufacture, a rail bond having a stranded conductor body, a terminal formed of the end of said body, and a metal sleeve surrounding said terminal, said sleeve being longitudinally split and formed at its inner end with a relatively thin, integral, flange-like extension flexibly encasing the corresponding portion of said body, the edges of such extension adjacent the split in said sleeve being formed to overlap.
- 15 6. As an article of manufacture, a rail bond having a stranded conductor body, a terminal formed of the end of said body, and a metal sleeve surrounding said terminal, said sleeve being formed from a blank of general triangular shape, whereby the outer end

thereof lies at an angle to its axis, and said sleeve being further formed with a relatively thin, integral, flange-like extension on its end corresponding with the base of such blank.

- 25 7. As an article of manufacture, a rail bond having a stranded conductor body, a terminal formed of the end of said body, and a metal sleeve surrounding said terminal, said sleeve being formed from a blank of general triangular shape, whereby the outer end thereof lies at an angle to its axis, and said sleeve being further formed with a relatively thin, integral, flange-like extension on its end corresponding with the base of such blank, such extension being of greater length than such base so as to overlap.

35 Signed by me, this 10th day of April, 1928.

FRANK H. NEFF.
